The ornamental design for a protective case for a portable smartphone, as shown and described.

DESCRIPTION

FIG. 1 is a top, right, front perspective view of a protective case for a foldable smartphone showing a first embodiment of the new design in a fully folded configuration;

FIG. 2 is a front view of the invention illustrated in FIG. 1; FIG. 3 is a rear view of the invention illustrated in FIG. 1; FIG. 4 is a right side view of the invention illustrated in FIG. 1;

FIG. 5 is a left side view of the invention illustrated in FIG. 1;

FIG. 6 is a top view of the invention illustrated in FIG. 1; FIG. 7 is a bottom view of the invention illustrated in FIG. 1;

FIG. 8 is a top, right, front perspective view of the invention of FIG. 1 showing the new design in a fully unfolded configuration;

FIG. 9 is a front view of the invention of FIG. 1 as shown in a fully unfolded configuration;

FIG. 10 is a rear view of the invention of FIG. 1 as shown in a fully unfolded configuration;

FIG. 11 is a right side view of the invention of FIG. 1 as shown in a fully unfolded configuration;

FIG. 12 is a left side view of the invention of FIG. 1 as shown in a fully unfolded configuration;

FIG. 13 is a top view of the invention of FIG. 1 as shown in a fully unfolded configuration;

FIG. 14 is a bottom view of the invention of FIG. 1 as shown in a fully unfolded configuration;

(Continued)

FIG. 15 is a top, right, front perspective view of a protective case for a foldable smartphone showing a second embodiment of the new design in a fully folded configuration; FIG. 16 is a front view of the invention illustrated in FIG. 15; FIG. 17 is a rear view of the invention illustrated in FIG. 16; FIG. 18 is a right side view of the invention illustrated in FIG. 16; FIG. 19 is a left side view of the invention illustrated in FIG. 16; FIG. 20 is a top view of the invention illustrated in FIG. 16; FIG. 21 is a bottom view of the invention illustrated in FIG. 16; FIG. 22 is a top, right, front perspective view of the invention of FIG. 16 showing the design in a fully unfolded configuration; FIG. 23 is a front view of the invention of FIG. 16 as shown in a fully unfolded configuration; FIG. 24 is a rear view of the new invention of FIG. 16 as shown in a fully unfolded configuration; FIG. 25 is a right side view of the invention of FIG. 16 as shown in a fully unfolded configuration; FIG. 26 is a left side view of the invention of FIG. 16 as shown in a fully unfolded configuration; FIG. 27 is a top view of the invention of FIG. 16 as shown in a fully unfolded configuration; and, FIG. 28 is a bottom view of the invention of FIG. 16 as shown in a fully unfolded configuration.

The broken lines in the drawings depict portions of the protective case for a portable smartphone that form no part of the claimed design.
